UNITED STATES PATENT OFFICE.

WILLARD A. SCHWARTZ, OF LOS ANGELES, CALIFORNIA, ASSIGNOR OF ONE-HALF TO
ANDREW J. BERRY, OF LOS ANGELES, CALIFORNIA.

PAPER-ROLL PROTECTOR.

1,126,577.

Specification of Letters Patent.

Patented Jan. 26, 1915.

Application filed March 30, 1914. Serial No. 828,159.

To all whom it may concern:

Be it known that I, WILLARD A. SCHWARTZ, a citizen of the United States, residing at Los Angeles, in the county of Los Angeles, 5 State of California, have invented new and useful Improvements in Paper-Roll Protectors, of which the following is a specification.

This invention relates to a paper roll 10 p-rotector.

In the transportation of large rolls of paper such as are employed in printing newspapers and the like, many rolls are damaged and rendered unfit for feeding to the 15 press by reason of their bursting as sometimes occurs in unloading, by reason of the great weight of the rolls and the internal pressure set up in shifting them from place to place.

20 It is the object of this invention to prevent the above difficulties by providing a means for binding the rolls to insure them against bursting and also protect their edges against mutilation.

25 Another object is to provide a binder for paper rolls which can be readily attached to and removed from the rolls and used a number of times.

A further object is to provide a detachable roll binder which can be adjusted to 30 rolls of various sizes.

The invention primarily resides in adjustable hoops for engaging and clamping the peripheral ends of the paper roll, and means 35 for adjustably connecting the end straps together on opposite sides of the roll to bind the roll longitudinally.

The invention is illustrated in the accompanying drawings, in which:

40 Figure 1 is a perspective view of the invention showing it as applied. Fig. 2 is a detail in elevation showing the adjustable construction of the end hoops. Fig. 3 is a detail vertical section on the line 3—3 of

45 Fig. 2. Fig. 4 is a detail in elevation of the hoop clamping means. Fig. 5 is a view in side elevation with parts broken away. Fig. 6 is a detail in elevation of the strap clamping means. Fig. 7 is a detail section on the 50 line 7—7 of Fig. 6 as viewed in the direction of the arrows.

More specifically, 10 indicates an ordinary paper roll of the clamps employed in the printing of newspapers and the like, which 55 is usually of comparatively great length and

diameter and of considerable weight. These rolls in being handled and transported from place to place are frequently damaged by bursting, and by the mutilation of the peripheral edges at its ends.

The present invention resides in a device 60 for binding the ends of the roll 10 and for securely holding the binding means in place, and at the same time bind the roll longitudinally, and includes a pair of hoops 11 and 12 65 which engage the ends of the roll, and are connected together by straps 13 and 14 extending longitudinally of the roll in opposite sides thereof. The hoops 11 and 12 are formed of two separable semi-circular members 15 and 16 which are adjustably connected together at one end, and detachably connected together at the opposite ends.

The adjustable connection of the members 15 and 16 is particularly illustrated in Figs. 75 2 and 3 and comprises a strap 17 rigidly mounted on the member 16 by means of rivets 18, which strap is designed to engage the free end of the member 15, and to retain perforations 19 in the latter in engagement with lugs 20 on the member 16. A series of perforations 19 are provided in the member 15 and are arranged in pairs at suitable intervals apart longitudinal thereof. A pair of lugs 20 are provided on the member 16 and are arranged in such position as to simultaneously engage a pair of the perforations 19 in the member 15. By this construction the diameter of the hoops may be 80 adjusted by varying the positions of the over-lapping end of the members 15 and 16 in relation to each other, and securing them in the adjusted relation by means of the perforation 19 and lugs 20.

Mounted on the free end of the member 95 15 is a rectangular link 21 which is pivotally connected to the member 15 by turning the end of the latter around one member of the link 21, and riveting the bent portion of the link to the main portion thereof by rivets 22 as shown in Fig. 5. Mounted on the outer end of the member 16 is a pair of spaced lugs 23 which carry a pivot pin 24, which extends through lugs 23 and through lugs 25, a clamping arm 26 and 100 forming a pivotal support for the latter. The arm 26 is of a width approximating that of a member 16 and is formed with a series of angular notches 27 on its upper face, which notches extend transversely of 105 110

the arm 26 and are adapted to engage the other member of the link 21 to connect the outer ends of the members 15 and 16, and bind the hoop on the roll 10 as hereinbefore described. Formed on the members 15 and 16 are inturned flanges 28 which are spaced any suitable distance apart and are arranged to project over the end of the roll as particularly shown in Fig. 1 to engage the roll 10 and permit of the hoops being connected together under strains without displacement.

The hoop connecting means 13 and 14 is here shown as consisting of chains 29 and 30 adapted to be detachably connected together at their outer ends with their inner ends connected to diagonal extending chains 31 and 32, and 33 and 34. The chains 31 and 32 on the chain 29 connect at their outer ends to the members 15 and 16 on the hoop 11 a short distance from their ends, and the chains 33 and 34 on the chain 31 connect in like manner to the members 15 and 16 of the hoop 12.

The means for clamping the chains 29 and 30 together consist of a plate 35 pivoted to the end link of the chain 29, and having a lockable arm 36 pivoted at 37 on its outer end, which arm is formed with transverse inclined channels 38 adapted to engage the end link of the chain 30.

In the operation and application of the invention, the hoops 11 and 12 are adjusted to approximately fit the ends of the paper roll by adjusting the lugs 20 in the perforations 19; this adjustment being such that the outer ends of the members 15 and 16 will be normally spaced a short distance apart. The link 21 is then engaged in one of the notches 27 on the arm 26 which is then rocked outwardly and over the pivot pin 24 to the opposite side thereof, thereby drawing the outer ends of the members 15 and 16 toward each other, and tightly binding the hoop in place on the end of the roll. The notches 27 are of such depth that when the arm 26 is moved to its clamped position as shown in Fig. 5, the engagement of the notches with the link 21 will dispose the link out of alinement with the pivot pin 24 on the inner side of the latter in such manner that the arm 26 will be normally retained in its

innermost position. When the hoops 11 and 12 have been thus secured to the ends of the roll the straps or chains 29 and 30 are connected together by means of the 55 clamping arm 36 which is engaged with the end link of the chain 30 and swung to the opposite side of the pivot 33 in the position shown in Fig. 7, thus drawing the chains 29 and 30 together in a taut condition, and 60 thereby exerting a pull on the hoops 11 and 12 to effectively bind the roll 10 longitudinally.

It is manifest that any number of the binding straps 13 and 14 may be applied 65 around the periphery of the roll 10 as occasion may require. Preferably the hoops 11 and 12 are formed of sheet metal and the straps 13 and 14 are formed of metallic chains, but it is manifest that other materials may be substituted therefore as occasion may require, for instance, the hoops and straps may be formed of leather or similar material.

What I claim is:

1. A paper roll binder, comprising end engaging hoops and means for connecting said hoops together to bind the roll longitudinally.

2. A paper roll binder, comprising a pair 80 of adjustable hoops adapted to engage the ends of a paper roll, means for clamping said hoops to bind the roll peripherally, and means for connecting the end hoops together to bind the roll longitudinally.

3. A paper roll binder, comprising a pair 85 of hoops formed of separable members adapted to be adjustably connected together, and having means for clamping the members together on the end of a paper roll, 90 means on the hoop members for engaging the end of the roll, and adjustable straps connecting the end hoops together by means of which the roll can be bound longitudinally.

In witness that I claim the foregoing I have hereunto subscribed my name this 20th day of February 1914.

WILLARD A. SCHWARTZ.
